US00D612944S

(12) **United States Design Patent**
Arbesman et al.

(10) **Patent No.:** US D612,944 S
(45) **Date of Patent:** ** Mar. 30, 2010

(54) **ADHESIVE HIP SUPPORT BRACE**

(76) Inventors: **Ray Arbesman**, 42 Burton Road, Toronto, ON (CA) M5P 1V2; **Kevin Jardine**, 505 Eglinton Avenue West Suite 302, Toronto, ON (CA) M5N 1B1

(**) Term: **14 Years**

(21) Appl. No.: **29/332,064**

(22) Filed: **Feb. 6, 2009**

(30) **Foreign Application Priority Data**

Aug. 6, 2008 (CA) 127441

(51) **LOC (9) Cl.** 24-04

(52) **U.S. Cl.** D24/190

(58) **Field of Classification Search** D24/189-192, D24/206; D29/100, 101.3, 120.1; D2/627, D2/702; 602/1-2, 4-8, 19-20, 26, 41, 54, 602/60-63, 65; 128/100.1, 876, 892, 894; 2/24, 162, 455; 219/211, 527, 544, 549

See application file for complete search history.

CLAIM

An ornamental design for an adhesive hip support brace, as shown and described.

DESCRIPTION

FIG. 1 is a top view of the adhesive hip support brace showing our new design; and,

FIG. 2 is a perspective view thereof.

The broken lines shown in the drawings are for illustrative purposes only and form no part of the claimed invention.

1 Claim, 2 Drawing Sheets
